UNITED STATES PATENT OFFICE.

WILLIAM A. NICHOLS, OF JANEVILLE, WISCONSIN, ASSIGNOR TO LOUIS A. AVERY, OF JANEVILLE, WISCONSIN.

PROGRAM-CLOCK.

1,248,419.

Specification of Letters Patent.

Patented Nov. 27, 1917.

Application filed February 15, 1916. Serial No. 78,450.

To all whom it may concern:

Be it known that I, WILLIAM A. NICHOLS, a citizen of the United States, residing at Janesville, in the county of Rock and State 5 of Wisconsin, have invented certain new and useful Improvements in Program-Clocks, of which the following is a specification.

My invention relates to new and useful 10 improvements in clocks and more particularly in program clocks, the primary object of my invention being the provision of a clock which may be set to give an alarm after a predetermined time and which may 15 be further set to give additional alarms either prior to such time or subsequent thereto in order that the clock may be employed in giving notification of time in regard to several events.

20 More particularly, my improved program clock is intended for use by fruit and vegetable canners and the like to indicate or give an alarm at the exact time that the "cook" should be taken from the oven. In 25 this connection, one of the primary objects of my invention consists in the provision of a program clock for this purpose which may be employed in giving a number of separate and independent signals and, consequently, 30 which may be employed in connection with a number of ovens or in connection with a number of different "cooks" in the same oven.

A still further object of my invention 35 consists in providing a clock of the above described character which, in addition to the ordinary dial for reading time, is provided with a pair of additional dial rings, one of which is driven at a predetermined 40 rate of speed by the works of the clock and the other of which is stationary and in effect forms the contact receiving ring of the clock, the signals of which are given electrically by the closing of a circuit through 45 a brush carried by the movable dial ring and a contact inserted in an opening formed in the fixed dial ring or signal ring.

In this connection, a further object of my 50 invention is to so construct the co-acting dial rings that the dial as a whole may be correctly read from any position.

With these and other objects in view, my invention will be more fully described, illustrated in the accompanying drawings, and

then specifically pointed out in the claim 55 which forms a part of this application.

In the drawings:

Figure 1 is a perspective view of my improved program clock;

Fig. 2 is a front elevation, a portion of 60 the fixed dial or signal ring being shown in section and a portion of the main dial being broken away;

Fig. 3 is a central vertical sectional view 65 of the clock;

Fig. 4 is a fragmentary perspective view of certain of the clockworks controlling the driving of the movable dial ring;

Fig. 5 is a diagrammatic view of the wiring system.

Corresponding and like parts are referred to in the following description and indicated in all the views of the drawings by the same reference characters.

My invention includes a substantially rectangular casing 10 having a hinged front closure 11. Mounted within this casing is a conventional clock mechanism 12 and a plurality of dry cells 13 supported by clamps 14 and making up the battery, indicated in 80 the diagram at 15 which energizes an electric gong 16 or other suitable signal preferably secured to the outside of the casing. The cells are preferably fastened to the casing itself and the works of the clock, as 85 shown, are secured to the inner face of the closure in order that they may be readily accessible upon opening of the closure. This closure is formed with an opening 17 through which the minute and hour hand 90 shafts 18 and 19, respectively, extend and through which also extends a shaft 20 suitably journaled in the face plates of the clock. The shafts 18 and 19 carry the minute and hour hands 21 and 22, respectively. The 95 minute hand shaft has fixed upon it a pinion 23 which meshes with a toothed wheel 24 loosely mounted upon an idler shaft 25 and connected to a pinion 26 which meshes with the toothed wheel 27 fixed upon the 100 hour hand shaft 19, these being the toothed wheels and pinions employed in transmitting power from the minute hand shaft, which is the drive shaft, to the hour hand shaft, these toothed wheels and pinions being common to substantially all clockworks.

In the present instance, however, I mount an additional toothed wheel 28 upon the

shaft 20, previously referred to, this toothed wheel meshing with the toothed wheel 24 and being so proportioned that it will turn its shaft 20 through a complete revolution 5 once every two hours. This shaft 20 also projects through the closure 11 of the casting.

Secured to the outer face of the closure 11 and concentrically with respect to the 10 shaft 20, is a metal disk 29 forming the true dial plate of the clock itself, this disk being inscribed with the usual hour and minute hand divisions, as shown at 30, and being apertured for the passage of the 15 hour and minute hand shafts and the shaft 20, none of the clock mechanism, however, touching the disk. This disk, adjacent its peripheral edge, is formed with a circular series of openings 31 equally spaced and 20 extending throughout the entire circumference of the disk, there being 120 of such openings. Co-acting with the shaft 20, is a movable dial ring 32 having a diametrically formed brace 33 provided centrally with 25 a hub 34 engaging about the shaft 20 to which it is secured by a set screw 35. Because of this, the dial ring will interfere but slightly with a view of the clock dial proper 30 in any position which it may 30 occupy. This dial ring is somewhat less in external diameter than the diameter of the circular outline of the openings 31 of the plate 29 and has its periphery marked off by a plurality of radial minute divisions, 35 as shown at 36, there being 120 of these divisions, each corresponding to one of the openings 31. This dial ring 32, at its 120th, which is also its zero division has an outwardly and radially resilient contact member or brush 37 which projects slightly beyond the openings 31 as the dial ring revolves.

The dial or face of the clock is covered by a door, indicated as a whole by the numeral 38 and including a transparent crystal 39 secured by locking buttons 40 to the inner face of the inwardly directed annular flange of a ring 41 which is hingedly connected to the closure 11 as shown at 42' to 45 swing upwardly and outwardly from the closure. As shown, the ring 41 is proportioned to clear the plate 29 at its peripheral edges and a set screw 42 threaded into the lower peripheral edge of the ring 41 is 50 adapted to engage between the fingers of a bracket 43 secured to the closure 11 and to be clamped against such fingers to hold the door 38 in place. The ring 41 forming the frame of the door has its inwardly 55 directed annular flange provided with a series of openings 44 corresponding to and one in alinement with each one of the openings 31 of the plate 29. This flange is also formed with radial inscriptions 45 60 projecting from the openings 44 and in ef-

fect forming continuations of the corresponding inscriptions or divisions 36 of the movable dial ring 32. These alined openings are adapted to receive the shanks of removable contact pins 46 in the manner 70 best shown in Fig. 3 of the drawings, any pin mounted in one of these pairs of alined openings, of course, projecting in the path of the brush 37. A plurality of these contact pins are provided each preferably having its head inscribed with a distinguishing number and when the pins are not in use, their shanks are seated in a series of openings 47 formed in the closure 11 adjacent its lower end. A conductor wire 48 leads from 80 one pole of the battery 15 to the bracket 43, a conductor wire 49 has electrical engagement with the shaft 20 and leads to one terminal of the bell 16, and a conductor wire 50 leads from the other terminal of this bell 85 to the other pole of the battery 15. It will, therefore, be seen that there is a circuit through the battery and bell normally open between the revolving dial ring 32 and the ring 41 forming a combined dial and signal 90 ring and that this circuit may be closed by engagement with the brush 37 with a contact pin passed through the ring 41.

In operation, assuming that a "cook" has just been placed in the oven, in which it 95 should remain for thirty minutes, one of the contact pins would be placed or passed through that opening 44 of the contact ring 41 which is then opposite the division of the revolving dial ring 32 marked 30. Under 100 these circumstances, the circuit through the signal would be automatically closed at the end of thirty minutes and the person in charge notified that the "cook" should be removed from the oven. Obviously, "cooks" 105 in any number of ovens or any number of "cooks" in the same oven may be timed by a signal clock by giving each of the "cooks" a number corresponding to the distinguishing number of the contact pin employed 110 with it. The program clock illustrated and described is capable of giving a signal at any time from one minute to two hours after it is set, which is usually sufficiently long for the purpose. Obviously, however, 115 it may be re-set as often as necessary and thus arranged to give a signal any number of hours after it was first set. Furthermore, I do not wish to limit myself to the employment of a movable dial ring which turns 120 once in two hours, in conjunction with a fixed dial or contact ring having 120 contact openings as the movable dial may be driven at such a speed as to revolve only once in two or three hours and the dial and contact ring may be formed with a correspondingly large number of contact pin receiving openings. By forming both the fixed dial and contact ring and the revolvable dial ring with radial inscriptions and 125 130

by mounting the latter immediately at the rear of the former, it will be clear that I provide an arrangement which may be easily read from any direction. Furthermore, although I have described the clock as particularly adapted for use by fruit and vegetable canners, it will be understood that it may be employed for any purpose in which indication of lapse of time is desirable, such as in connection with washing machines, driers and the like. For this reason, I do not wish to limit myself to any specific features or details of construction other than those embodied in the claim.

Having thus described the invention, what is claimed as new is:

In a program clock, a swingingly mounted

non-rotatable dial ring provided with an annular series of openings, a two-part fastener for securing the dial ring in normal position, one part of the fastener being carried by the ring, a clock driven revoluble dial ring provided with circumferential scale divisions corresponding to the openings, a brush carried by the revoluble ring, a contact insertible in one of the openings of the fixed dial ring to extend in the path of the brush, a circuit including the fixed and revoluble dial rings and the two parts of the fastener normally open between the brush and contact, and a signal device in the circuit.

In testimony whereof I affix my signature.

WILLIAM A. NICHOLS. [L.S.]
